(57) **CLAIM**

We claim the ornamental design for a dishwasher detergent dispenser, or similar article substantially as shown.

DESCRIPTION

FIG. 1 is a perspective view of the dishwasher detergent dispenser of the present invention.

FIG. 2 is a top plan view of the dispenser with the lid in a closed position.

FIG. 3 is a right side elevation view of the dispenser.

FIG. 4 is a left side elevation view of the dispenser.

FIG. 5 is a right end elevation view of the dispenser; and,

FIG. 6 is a left end elevation view of the dispenser.
Applicant makes no claim to the bottom of the dispenser
which is not visible when the dispenser is mounted in a
dishwasher door.
